METHOD OF AND APPARATUS FOR MANUFACTURING THREAD OR THE LIKE

Richard F. Bergmann, Lakewood, Ohio, assignor
to Industrial Rayon Corporation, Cleveland,
Ohio, a corporation of Delaware

Application September 28, 1939, Serial No. 296,936

10 Claims. (Cl. 34—23)

This invention relates to methods of and apparatus for manufacturing strip material such as thread, filaments, bands, etc. (hereinafter referred to as "thread"). More particularly, it relates to methods and apparatus capable of being employed in continuous processes pursuant to which the thread is continuously but temporarily stored in a series of generally helical turns on a plurality of thread-advancing thread store devices. Among other things, the invention involves a system in which a treating medium is circulated through each of at least two different thread-advancing thread store devices to which the thread passes in series, in consequence whereof the same treating medium may be employed to treat the same thread a plurality of different times.

The invention has particularly significant advantages when employed in a process in which the thread, while being continuously but temporarily stored on at least two thread-advancing thread store devices, is subjected to the action of a temperature-changing medium. In such a process, the thread may be subjected to the action of a temperature-changing medium circulated in turn through a plurality of thread-advancing thread store devices on which the thread is stored for treating purposes; for example, for the purpose of drying the thread, with an intermediate rewetting step, a plurality of different times. The importance of this and other advantages of the invention will be more clearly apparent from the following description of the invention.

For convenience, the invention will be described in connection with the manufacture of multiple filament viscose artificial silk thread on apparatus similar to that disclosed in copending application Serial No. 275,919, filed May 26, 1939, for "Apparatus for the manufacture of thread or the like" (Patent 2,284,497).

In the drawings, Figure 1 represents an end elevation of such apparatus, portions of the processing liquid circulation systems being omitted and other parts being broken away for the sake of clearness. Figure 2 represents a sectional elevation on an enlarged scale of a portion of the apparatus of Figure 1, such portion comprising the last four thread-advancing reels in a single descending series on the left-hand side of the apparatus. Figure 3 is an end elevation on a still larger scale of one form of thread-advancing reel employed for drying the thread. Figure 4 represents a longitudinal sectional elevation of said reel on line 4—4 of Figure 3. Figure 5

is a sectional elevation on the same scale as Figures 3 and 4 of another type of thread-advancing reel employed for drying the thread.

Figure 1 shows an end elevation of a complete machine for continuously manufacturing a plurality of multiple filament viscose artificial silk threads 1 individually characterized by a low residual capacity to shrink. Each thread is formed by the extrusion of viscose from a spinneret into a suitable coagulating bath contained in a trough (not shown) disposed in the hooded upper portion 2 of the apparatus. Each thread passes in sequence to a concatenate series of thread-advancing reels on each of which it is continuously but temporarily stored in a large number of closely spaced generally helical turns which are automatically advanced lengthwise of the reel by the action of the elements thereof.

As shown in Figure 2, thread-advancing reels 4, 5, 6 and 7 are of cantilever construction, each being supported exclusively from one end thereof. During rotation of the reel, each advances the thread toward its unsupported end in a large number of closely spaced, generally helical turns. On several such reels, particularly those disposed above reel 4, suitable liquid processing operations, such as washing, desulphurizing, etc., are performed on the thread, while on reels 5, 6 and 7 the thread is dried, remoistened and redried. From the last reel in the series, the thread passes to a suitable collecting device, such as cap-twister 3, which collects the finished thread in package form.

As is apparent from Figure 2, the reels of each series are disposed in stepped arrangement with the unsupported or discharge end of each preceding reel in opposite relation to the supported or receiving end of each succeeding reel, the unsupported ends of all reels extending in one and the same direction. A plurality of such series of reels are disposed longitudinally of the apparatus on each side thereof, so that the apparatus as a whole has an operating face extending along each of its two sides. Corresponding parts of all descending series of reels on both sides of the apparatus are in corresponding positions lengthwise thereof. As shown in Figure 1, the thread processing section of the apparatus takes the form of two oppositely extending banks of reels which are inclined toward each other at the upper portions thereof.

The reel 4 of Figure 2 is typical of the reels preceding it in the series, being similarly constructed, arranged and employed. The desired processing liquid is supplied to the reel 4 from

a reagent distributor 8 communicating with a conduit 9 which extends longitudinally of the machine, such conduit being formed integrally with the lower portion of collecting trough 11 disposed beneath the preceding reel. Collecting troughs 11 are disposed beneath all reels from which liquid drips from the thread: each such trough extends beneath a horizontal series of corresponding reels on the same side of the apparatus.

The desired processing liquid is applied to the thread on reel 4, and on preceding reels on which liquid is applied to the thread, at the unsupported end of the reel. Under normal conditions of operation, it forms a traveling film of liquid extending uninterruptedly around the entire thread-bearing periphery of the reel. In the apparatus illustrated in the drawings, reel 4 is inclined to the horizontal in order that the film of liquid may travel along the reel from the unsupported end toward the supported end thereof, thus providing a countercurrent flow of liquid which more effectively processes the thread.

These conditions do not occur on reels 5 and 6, but from a constructional standpoint it is convenient to tilt them also.

In the practice of the invention, thread which has never been dried; i. e., thread which is still in a gelatinous state, is subjected to repeated drying with intermediate rewetting on a plurality of reels. However, the idea of continuously drying the thread a plurality of times with intermediate rewetting forms no part of the present invention, but is shown, described and claimed in copending application Serial No. 297,074, filed September 29, 1939, by Hayden B. Kline and Louis S. Fryer (Patent 2,286,213). Rather, the present invention constitutes in a sense an improvement upon the invention disclosed in that application.

In the present embodiment, the thread passing from reel 4 is first substantially completely dried on reel 5, which, being of a metal of good heat conductivity such as aluminum, is advantageously heated by the circulation therethrough of a suitable heating medium. Just before the thread leaves the unsupported end of reel 5, it is subjected to the action of a small stream of rewetting liquid from a reagent distributor 12 supplied from a conduit 9 forming part of the trough 11 disposed beneath the preceding reel 4. The liquid thus applied to the reel is not sufficient in amount to spread over the entire reel, but only enough to wet thoroughly a number of the last few turns of thread thereon.

From reel 5 the wet thread passes to reel 6, which, in the illustrated embodiment of the invention, constitutes a drip reel. No processing liquid is applied to the thread stored on said reel 6; instead, liquid applied to the thread on the preceding reel 5 is permitted to drip from the thread. A substantial length of thread is stored on the reel 6; consequently, when the thread reaches the discharge end of reel 6, all portions of the thread have substantially the same moisture content. In a sense, therefore, said reel 6 constitutes a means for equalizing the moisture content of the thread.

The thread passing to reel 7, being already characterized by a uniform moisture content, may then be uniformly dried by subjecting it to uniform drying conditions. To aid in maintaining the uniformity of drying conditions, an enclosure 13 is provided surrounding each reel 7. Said enclosure comprises a stationary portion 14 and a hinged closure portion 15, slots 16 and 17 being

provided at the junctures of said hinged and stationary portions to permit the thread 1 to enter and to leave said chamber in passing to and from reel 7 disposed therein. A similar enclosure may, 5 of course, be provided for reel 5, if desired.

Drying reels 5 and 7 are tapered in the direction of advance of the thread to permit it to shrink during drying, which imparts a low residual shrinkage capacity to the thread.

10 As appears from Figure 2, the invention contemplates the circulation of a liquid heating medium in series through each of reels 5 and 7. The heating liquid is supplied from a conduit 18 which extends lengthwise of the apparatus along 15 each side thereof and serves all drying reels on the same side of the apparatus. It passes from said conduit 18 through control valve 19 and tube 21 to the first drying reel 5, communicating with said drying reel by means of a pipe 22 which is 20 connected to said drying reel and coupled to tube 21.

After circulating through drying reel 5, the heating liquid passes through pipe 23 which is coupled to a tube 24 connected to the entrance 25 port of drying reel 7. The liquid circulates through drying reel 7, after which it passes through tube 25 which communicates through valve 26 with discharge conduit 27, which, like supply conduit 18, extends lengthwise of the machine and serves all of the drying reels on one side thereof. By means of valves 19 and 26 the flow of the heating liquid through reels 5 and 7 can be easily shut off or the flow through the reels from end to end of the apparatus equalized.

35 In the apparatus illustrated, such an arrangement of tubes and piping is supplied for each pair of reels 5 and 7 serving to dry a single thread.

As shown in Figure 1, supply conduits 18 on 40 opposite sides of the apparatus are connected by a cross pipe 28 which communicates through a pipe 29 with a supply tank 30 disposed at the upper portion of the apparatus. Supply tank 30 is accessible for servicing and inspection purposes from platform 31 from which the spin trough, 45 spinnerets, etc., are accessible. It is provided with heating elements 33 heated by steam circulated therethrough by supply pipe 34 and condensate return pipe 35. A valve 32 is provided between each conduit 18 and pipe 29 to regulate 50 the supply of liquid to conduit 18.

Discharge conduits 27 on opposite sides of the apparatus communicate through pipes 36 with a sump tank 37. Valves 38 may be provided in said pipes 36 to control the flow of heating liquid. The liquid in sump tank 37 is removed through pipe 39 which communicates with the centrifugal pump 41 driven by motor 42. Pump 41 forces the liquid from the sump tank 37 upwardly through pipe 43, in which is a valve 44 to control the 60 discharge of said pump, to the supply tank 30.

More liquid is supplied through said pipe 43 than is removed through pipe 29, the excess flowing out of tank 30 through overflow pipe 45 which 65 communicates with sump tank 37. Overflow pipe 45 therefore determines the level of the liquid in said supply tank 30. Thus a constant gravity pressure is maintained on the supply conduits 18 on opposite sides of the apparatus with the result that an accurate, constant flow of fluid can be obtained through all of the reels 5 and 7 of the apparatus.

The various pipes and conduits conducting the heating liquid, the steam pipes, and supply tank 70 30 are preferably suitably insulated to minimize

heat losses. Suitable control mechanism may be provided in conjunction with steam lines 34 and 35 accurately to control the heat input, and consequently the temperature, thereof. A closed system for the recirculation of the heating fluid is therefore provided.

Each of the various reels employed in the illustrated apparatus comprises two wholly rigid reel members. Each of said reel members is of substantially circular cross section. Each has a periphery made up of a plurality of longitudinally extending bar members which are interleaved with the bar members of the other reel member. The reel members of the reel rotate about axes offset from and inclined to each other in such manner as to advance the thread continuously in a large number of closely spaced, generally helical turns from the supported to the unsupported end of the reel.

As is apparent from Figures 3 and 4, reel 5 comprises two rigid reel members 47 and 48. Member 47, which may be termed the concentric member, is mounted concentrically upon and for rotation with hollow drive shaft 49. Its periphery comprises a plurality of spaced, longitudinally extending bar members 51. Member 48, which may be termed the eccentric member, is mounted with its axis inclined to but in a plane slightly offset from the axis of reel member 47. Its periphery is made up of a plurality of spaced, longitudinally extending bar members 52 alternately disposed with respect to bar members 51 of concentric reel member 47.

Concentric reel member 47 may be formed, as shown, with the bar members 51 integral with hollow body portion 53. Front and rear closure members 54 and 55, respectively, form fluid-tight junctions with hollow body portion 53. Said members also surround and are supported from hollow drive shaft 49. Cooperating annular sealing members 56 which are wedge-shaped in cross section, disposed in recesses 57 in members 54 and 55, prevent the escape of fluid from the interior of reel member 47 past the shaft.

A bolt 58, holding a washer 59 against the outer sealing member 56 at the unsupported end of the reel, is threaded into a plug 61 secured, as by being welded, in the unsupported end of hollow drive shaft 49. A washer 62, located on drive shaft 49, as by the snap ring 63 shown, bears against the outer sealing member 56 at the rear of the reel member 47, thus locating said reel member endwise on the shaft. Moreover, as the bolt 58 is tightened, it forces the wedge-shaped sealing members 56 together at both ends of the reel member 47, thus effectively sealing said reel member and providing tight fits at these points on the shaft 49, whereby driving engagement of member 47 with said shaft is provided.

In the reel of Figures 3 and 4, eccentric member 48 is formed of a rigid cagelike member 64 mounted concentrically upon a rotatably mounted supporting member 65, as by bolts 66. Rigid cagelike member 64 comprises the aforementioned bar members 52 which are fixed at their supported ends to an annular external supporting rib 67 by means of which the cagelike member 64 is mounted on said supporting member 65. An annular reinforcing member 68 is fixed to the bar members 52 at their unsupported ends. Supporting member 65 is mounted on a frame member 69 for rotation about an axis disposed in the desired offset and inclined relation with respect to the axis of rotation of concentric member 47.

Supporting member 65 is concave, as shown, in order that the projecting boss 71 on frame member 69 on which said supporting member 65 is mounted by means of antifriction bearings 72 may be disposed within the reel proper. The purpose is to provide an arrangement in which, even though fluid supply and removal means are associated with the frame member 69 of the reel, the overall length of the reel and its supporting member is only slightly, if at all, greater than that of reels 4 and 6, thus making it possible to substitute one of the reels 5 for any of the reels other than reel 7. Reel 5 is similar to all other reels illustrated in that its frame member 69 is provided with a flange portion 73 (Figures 2 and 4) adapted to fit closely and be held in a cup 74 fixed to the frame of the apparatus, as shown in Figure 2. Set screws 75 may be threaded into said cup to hold the flange member therein.

Drive shaft 49, on which concentric member 47 is mounted, passes longitudinally through said frame member 69, being journaled therein by spaced bearings 76 and 77. In the reel of Figures 3 and 4, an annular internally toothed member 78 fixed to the inner wall of hollow body portion 53 meshes with external teeth 79 formed on supporting member 65, thus providing means for driving the eccentric member from the concentric member without contact of the bar members of the reel members, wherefore wear of the reel members is avoided. Bevel gear 81 fixed to the rear end of drive shaft 49 meshes with bevel gear 82 mounted on inclined drive shaft 83. Each of the other reels is similarly driven from said drive shaft 83.

Reel 5 is heated by the circulation of a suitable heating liquid through the hollow body portion 53 of concentric reel member 47. To this end, frame member 69 is hollow as shown in Figure 4, being constructed in such a way as to provide two compartments 84 and 85 through which the drive shaft 49 passes. Suitable sealing means 86 are shown as provided in said compartments to prevent the escape of heating fluid from the interior of said compartments past the drive shaft, either from one compartment to the other or to the atmosphere.

Each seal comprises a smooth-faced stationary member 87 against which bears a rotatable bearing member 88 urged thereagainst by a spring 89. Spring 89 is compressed between a flexible annular sealing member 91 seated on member 88 and a support 92 rigidly fixed to the drive shaft 49, as by set screw 93. The support 92 in compartment 84 serves seals 86 therein, which prevent the escape of fluid from either side of said compartment; the support 92 in compartment 85, the single seal 86. Said seals aid in locating the drive shaft 49, and consequently the concentric reel member 47, in proper relation to the other parts of the reel.

Compartment 84 is provided with an opening 94 through which the heating liquid is supplied from pipe 22. The heating liquid passes through a port 95 in the wall of hollow drive shaft 49, thence longitudinally of said drive shaft, and finally through port 96 into the interior of hollow body portion 53 of concentric reel member 47. It passes out of said hollow body portion 53 through an opening 97 in said drive shaft, which opening communicates with an inner tube 98 in said drive shaft.

The plug 61 at the unsupported end of drive shaft 49 serves to separate the inner tube 98 and the drive shaft; also, to prevent the heating

liquid from passing directly from the drive shaft to the tube and vice versa. A similar plug 99 at the rear portion of said drive shaft 49 prevents the intermixing of the entering and discharging fluid. The heating liquid passes from said inner tube 98 through port 101 into the rear compartment 85 from which it passes out through opening 102 to discharge pipe 23.

The above-described reel 5 comprises the subject matter of copending application Serial No. 296,937, filed September 28, 1939, by Richard F. Bergman (Patent 2,281,406).

Reel 7, which differs from reel 5 in the respects hereinafter pointed out, operates in a generally similar manner. It comprises two wholly rigid reel members 47a and 48a. Concentric reel member 47a is mounted concentrically upon and for rotation with hollow drive shaft 49a, its periphery comprising a plurality of spaced, longitudinally extending bar members 51a. Member 48a, which may be termed the eccentric member, is rotatably mounted with its axes slightly offset from and inclined to that of member 47a. Its periphery is made up of a plurality of spaced, longitudinally extending bar members 52a alternately disposed with respect to bar members 51a of reel member 47a.

Concentric member 47a is formed with its bar members 51a integral with hollow body portion 53a. Members 54a and 55a, forming fluid-tight junctions with the inner surface of said hollow body portion 53a, close off the ends of said body portion and serve as means for mounting the reel member 47a on drive shaft 49a. Reel member 47a is held on drive shaft 49a against a collar 63a fixed to said drive shaft by bolt 58a threaded into the end of said drive shaft. Packing 103 disposed in a recess 57a in closure member 55a, and in a recess in member 54a in which it is compressed between drive shaft 49a and bolt 58a, operates to prevent the escape of heating fluid from the interior of body portion 53a past the drive shaft 49a. The tight fit of reel member 47a on said drive shaft and the compression afforded by bolt 58a provides rigid driving engagement between said reel member and said drive shaft.

Eccentric reel member 48a is formed of a rigid cagelike member 64a mounted concentrically and rigidly upon a rotatable supporting member 65a by means of bolts 66a. Rigid cagelike member 64a comprises the bar members 52a fixed at their supported ends to an external annular reinforcing rib 67a, by means of which said cagelike member 64a is mounted on rotatable supporting member 65a, and an annular reinforcing rib 68a fixed to the bar members 52a at their unsupported ends. Supporting member 65a is mounted by means of spaced antifriction bearings 72a upon frame member 69a for rotation about an axis disposed in the desired offset and inclined relation with respect to the axis of rotation of concentric member 47a. An externally toothed member 79a mounted on the rear closure member 55a of concentric reel member 47a engages the teeth of an annular internally toothed member 78a mounted on supporting member 65a.

Shaft 49a is journaled in said frame member 69a by means of a bearing 76a disposed at the unsupported end of said frame member and by antifriction bearing 77a supported in a cross member 104 fixed to the spaced, longitudinally extending members 105 forming part of frame member 69a. Shaft 49a is located against endwise movement between collar 63a and collar 106

bearing against the inner race of said antifriction bearing 77a. It is rotated by means of bevel gear 81a mounted on said shaft between longitudinally extending members 105, which bevel gear meshes, as hereinabove described, with a corresponding gear on inclined drive shaft 83.

Frame member 69a is provided with a flange portion 73a adapted to fit closely in and to be held in cup member 74a fixed to the frame of the apparatus; consequently, reel 7 is demountably supported by the apparatus.

The means for circulating heating liquid through the reel is generally similar to that already described. A fitting 107 mounted on the longitudinally extending members 105 of frame member 69a is provided with two compartments 84a and 85a. The drive shaft 49a projects into the forward compartment 84a while the tube 98a, fixed in said hollow drive shaft 49a, extends into the rear compartment 85a. Suitable plugs 61a and 99a are provided in said hollow drive shaft 49a to support inner tube 98a and to prevent liquid from passing directly from the hollow drive shaft to the inner tube or vice versa. Suitable sealing means 86a are provided to prevent the escape of liquid from compartment 84a past the drive shaft 49a or from compartment 85a into compartment 84a.

Heating liquid is supplied as hereinbefore described from the preceding reel 5 through tube 24 to compartment 84a through opening 94a and passes through ports 95a into the space between the inner tube 98a and the inner surface of hollow drive shaft 49a. The liquid passes out of said hollow drive shaft through ports 96a into the interior of body portion 53a of concentric reel member 47a. After circulating through said body portion, the heating liquid passes through ports 97a into the inner tube 98a, from which it is discharged into the rear compartment 85a. The heating liquid passes out of said compartment through opening 102a which communicates with discharge tube 25.

If, as in the illustrated embodiment of the invention, a liquid is employed as the heating medium, the temperatures which it is desired to obtain will largely determine the nature of the liquid; for example, for temperatures below the boiling point of water, hot water may conveniently be employed as the heating medium. Of course, under suitable circumstances gaseous or vaporous heating media may be employed, such, for instance, as steam. However, better temperature control is obtainable when a liquid heating medium is employed.

In the operation of apparatus of the type illustrated it has been found desirable to produce a temperature on the reel devoted to the first drying of a thread; i. e., reel 5, which is substantially above the boiling point of water, this for the reason that beneficial effects are obtainable from a combination of high temperature and the contemporaneous application of a rewetting liquid at the unsupported end of said reel. On the reel devoted to the second drying of the thread; i. e., reel 7, a temperature substantially below the boiling point of water is desirable, since more complete shrinkage of the thread is possible under such conditions. Consequently it is beneficial to pass the heating liquid first to the reel on which the highest temperature is desired. By suitable design, the temperature drop in the heating liquid during its passage through the reel will be such that the liquid will have a lowered heat content

sufficient to heat the second reel to the desired lower temperature.

If it is desired to employ a liquid as a heating medium under such circumstances, it is desirable to use one which has a boiling point sufficiently above that of water to permit the desired high temperature to be attained on reel 5. In such case, a high boiling-point liquid, such as mineral oil, diethylene glycol or the like may be employed. The closed recirculation system of the invention provides great advantages under such circumstances in that it prevents the loss or waste of the heating liquid.

It is obvious that the illustrated embodiment of the invention is merely illustrative and that various modifications may be made therein without departing from the spirit of the invention. For example, other types of thread-advancing thread store devices than those illustrated may be employed, although those illustrated have been found in practice to be especially advantageous. Moreover, the invention may be employed for uses other than that in connection with which it has been described. For example, the methods and apparatus of the invention may be employed in a process wherein a refrigerating rather than a heating fluid is circulated in series through several thread-advancing thread store devices.

The present invention, moreover, is not restricted to methods or apparatus for the processing of thread per se, but may be employed in connection with the treating of any kind of strip material. In the appended claims the term "thread" is intended to include, besides thread per se, all types of materials to the treatment or handling of which the present invention is applicable. It is intended that the patent shall cover, by suitable expression in the appended claims, whatever features of patentable novelty reside in the invention.

What is claimed is:

1. Apparatus for continuously treating thread comprising at least two thread-advancing thread store devices to which the same thread passes in series, each of said thread store devices being made up of a plurality of interdigitating sets of bar members; means associated with the interior of each of said thread store devices for circulating a temperature-changing fluid therethrough; and means for passing the same temperature-changing fluid which has been passed through and has left one of said thread store devices through at least one other of said thread store devices.

2. Apparatus for continuously treating thread comprising at least two thread-advancing thread store devices to which the same thread passes in series, each of said thread store devices being made up of a plurality of interdigitating sets of bar members; means associated with the interior of each of said thread store devices for circulating a heating medium therethrough; and means for passing the same heating medium in series through at least two of said thread store devices, said means including apparatus for re-

65 heating said heating medium after it leaves the last of said thread store devices and recirculating it back to said first thread store device.

3. Apparatus for continuously treating thread comprising at least two hollow thread-advancing thread store devices to which the same thread passes in series, each of said thread store devices being made up of a plurality of interdigitating sets of bar members; supply and discharge ducts associated with each of said thread store devices for circulating a temperature-changing fluid through the hollow interior thereof; conduit means connected to the supply duct of one of said thread store devices for supplying the temperature-changing fluid to said duct; conduit means connected to the discharge duct of another of said thread store devices for removing the temperature-changing fluid from said discharge duct; and means connecting the discharge conduit of the former thread store devices with the supply conduit of the latter thread store device.

4. The method of subjecting thread to the action of a temperature-changing fluid comprising the steps of impressing upon a substantially continuous thread the form of a plurality of successive traveling helices each of which is characterized by a plurality of closely spaced turns, subjecting one of said helices to the action of the temperature-changing fluid at a predetermined temperature whereby the temperature of said fluid is altered and thereafter subjecting another of the helices to the action of the temperature-changing fluid to the action of which the helix mentioned in the preceding step has previously been subjected.

5. The method described in claim 4 wherein the temperature-changing fluid following the completion of the last step is restored to its original predetermined temperature and the steps are repeated.

6. The method described in claim 4 wherein the temperature-changing fluid is a liquid.

7. The method described in claim 4 wherein the temperature-changing fluid is a liquid having a boiling point above the boiling point of water.

8. The method described in claim 4 wherein the temperature-changing fluid is heated to a temperature above the boiling point of water.

9. The method described in claim 4 wherein at least two successive helices are formed in the thread, the first of said helices being subjected to the action of a temperature-changing fluid at a predetermined temperature and the last of said helices being subjected to the action of the same temperature-changing fluid at a lower temperature.

10. The method described in claim 4 wherein at least two successive helices are formed in the thread, the first of said helices being subjected to the action of a liquid heated to a temperature above the boiling point of water and the last of said helices being subjected to the action of the same liquid at a lower temperature.

RICHARD F. BERGMANN.
